UNITED STATES PATENT OFFICE.

SIDNEY H. MICHAELS, OF OAK PARK, ILLINOIS, ASSIGNOR TO WALTER P. MURPHY, OF CHICAGO, ILLINOIS.

DROP-END GONDOLA CAR.

1,284,413.

Specification of Letters Patent. Patented Nov. 12, 1918.

Application filed August 1, 1917. Serial No. 183,878.

To all whom it may concern:

Be it known that I, SIDNEY H. MICHAELS, a citizen of the United States, residing at Oak Park, in the county of Cook and State 5 of Illinois, have invented certain new and useful Improvements in Drop-End Gondola Cars, of which the following is a specification.

My invention relates to the construction of 10 drop end gondola cars, and more particularly to the end structure in a car of this type.

Drop end gondola cars are used for the transportation of a variety of cargoes. They 15 may be used, as the ordinary gondola car is used, for material in bulk, such as coal, sand or gravel; or, with the end panels folded down upon the flooring of the car, they may be employed for the transportation of long 20 timbers, girders, rails, or freight of this character.

One of the objects of my invention is to provide, in a drop end gondola car, means 25 for hinging the end panel or folding end of the car to the body of the car, whereby, when the car is used for bulk freight, the hinge will not be clogged by the material with which the car is loaded. It has been customary to cut away the flooring at the end of the 30 car to form a recess for the lower edge of the end panel and its hinges. This recess is likely to become filled, when bulk freight of pulverulent or granular material is carried, so as to clog the hinge and make it difficult 35 to fold down the end of the car when required. My invention provides an arrangement whereby the end rests directly on the floor, which latter extends out to the end framing of the car, the end being hinged by 40 devices so constructed and disposed that they cannot become clogged.

A further object is to provide a hinge for the folding end panel of a drop bottom car, which will be very strong and durable and 45 will consist of a few parts of simple construction. Another object is to construct and arrange the parts of the hinge so as to face the end panel.

A further object of the invention is to 50 provide an improvement upon the construction of the end panel in a car of this type, whereby this part of the car will be very strong, rigid and durable to withstand the rough handling to which it is necessarily subjected when the car is in service.

The invention consists in the novel and improved constructions, arrangements and devices, to be hereinafter described and claimed, for carrying out the above stated objects and such other incidental objects as 60 will appear from the following description.

The invention is illustrated, in a preferred embodiment, in the accompanying drawing, wherein—

Figure 1 is an end elevation of a gondola 65 car constructed in accordance with the invention.

Fig. 2 is a fragmentary sectional view, on an enlarged scale, taken on line 2—2 of Fig. 1. 70

Fig. 3 is a detail sectional view on line 3—3 of Fig. 1.

Fig. 4 is a plan view of one corner of the car.

Fig. 5 is a view, in perspective, of one of 75 the keeper plates employed in forming the hinge between the end panel and the under frame of the car.

Fig. 6 is a similar view of one of the hinge forming T links, and 80

Fig. 7 is a similar view of a pair of angle plates for hinging the T link to the end sill.

Like characters of reference designate like parts in the several figures of the drawing.

Referring to the drawing, the corner posts 85 of the car, indicated at 10, 10, consist preferably of heavy angle bars. The side walls 11, which are shown as made of wood, are secured between the corner posts 10 and supplemental inner post members 12, 13. 90 16 indicates the end sill proper of the car shown as consisting of a channel bar. To the upper flange of the channel bar is secured an extension plate 14, forming, in effect, part of the sill, and provided with an upstanding flange 15 which is riveted to the corner posts 10. 16 indicates the flooring of the car which extends to the corner posts 10 and to flange 15 of sill member 14. 95

It will be evident that my invention is not 100 limited to the precise details of construction above described. The door and its hinging mechanism, to be hereinafter described, might be applied, for example, to a car of all steel construction instead of to the car 105 of the type shown in the drawing. In fact, it is applicable to any of the common types of drop end gondola cars.

The end panel or hinged end of the car 110 comprises, preferably, a horizontally corru-

gated sheet of metal 17 to the outside of which is riveted, at suitable intervals a preferably flat metal sheet 18. The upper margin of the panel is suitably reinforced preferably by an angle bar 19, the ends of which are secured by small angles 20 to the edges of one of said metal sheets, for example, the outer sheet 18. With the end panel so constructed, it will be very strong and rigid. 10 This is desirable both so that it will withstand cargo thrusts and pressures when in upright position, and so that it will also carry, without being crushed or injured, the heavy loads which are likely to be put upon it when folded down on the floor of the car. 15 For example, when the car is loaded with rails, beams or girders which are longer than the interior longitudinal dimension of the car, the ends are folded down on the floor and the girders, or other such articles, rest 20 with their extremities upon such end panels. In the construction described the corrugations give rigidity to the panel which is increased by the expedient of riveting the flat sheet at intervals to the corrugations of the 25 corrugated sheet.

The panel is hinged to the under frame of the car by two link hinges, each constructed preferably as follows: 22 is a T-shaped link having an eye 23 pivoted by a bolt 24 between angular supports 25 (Fig. 7) which are riveted to the sill plate 14 and stand against the flange 15. The link extends through alining slots 26 formed in the flange 15 and the lower edges of sheets 17, 30 18, and through a slot 27 in a U-shaped keeper plate 28 which has legs of unequal length, the longer leg 29 being riveted to the lowermost corrugation 30 of sheet 17, the shorter leg being formed with ears 31 riveted to the flat marginal portions of sheets 17 and 18. The link 22 has a cross-piece 32 which lies within the space inclosed by the keeper plate and the lower edge of the panel. 40 The curved portions 33 of the U-shaped keepers 28 rest on the flooring 16 of the car, forming rounded bearings on which the panel may turn when it is folded up or down. 45

It will be seen that when the car is loaded 50 with pulverulent or granular material there is no danger of the hinge being clogged. The pivoted ends of the links are located outside of the car. The spaces between the keeper plates and the inner lower margin 55 of the panel are large enough so that the freedom of movement of the inner ends of the links cannot be hampered even if the material should pack into these spaces. Besides this, the keeper plates being relatively narrow and open at both ends, any material that gets in behind them will be loosened and fall out when one starts to fold down the panel. The T-shaped link provides with its keeper supporting bracket a hinge consisting of a very few parts of strong and

durable construction. Furthermore, with the head of the T against the keeper, which is the preferred arangement, the hinge forms a brace for the panel, transmitting the thrust of the cargo on the inside of the end 70 panel to the end sill, thereby lessening the tendency of the end to bulge.

The panel is held in its upright position against the end posts 10 by any suitable means. I have shown a pair of latch bars 75 34 fastened to the panel by staples 35 and having hook-shaped ends 36 adapted to engage clips 37 on the end posts.

The panel is preferably designed so that when folded down on the floor, as shown in 80 dotted lines in Fig. 2, the side flanges 20, angle 18 and keeper plates 28 touch the floor. The construction is such that the panel can take very heavy loads when in this position, without being crushed, broken or otherwise 85 injured.

While I have described my invention in a preferred embodiment, it will be understood that modifications might be made without departure from the principles of the invention. 90 Therefore I do not wish to be understood as limiting the invention to the precise constructions, arrangements and devices shown and described except so far as expressed in the claims. By the term "corner 95 post" as used in the claims I intend any upright member at the end of the car against which the end panel bears when in its raised position.

I claim:

1. In a drop end gondola car, the combination with the corner posts and flooring of the car, of an end panel, the lower edge of which is supported on the flooring when the panel is in upright position, and hinge 10 forming elements connected with the lower edge of the panel and with the car at points outside of said end panel.

2. In a drop end gondola car, the combination with the corner posts and flooring of 11 the car, the latter extending out to the corner posts, of an end panel, and hinge forming elements connected with the lower edge of the panel and with the car at points outside of said end panel.

3. In a drop end gondola car, the combination with the corner posts and end sill of the car, the latter extending outwardly beyond the corner posts, of an end panel, and means for hinging the lower ends of the 12 same to said end sill at points outwardly of the end corner posts.

4. In a drop end gondola car, the combination with the corner posts and end sill of the car, the latter extending outwardly 13 beyond the corner posts, of an end panel, the lower edge of which is formed with slots, hinge forming links pivoted to the end sill at points outside of said end panel and projecting through said slots in the same.

- and means on the inside of the panel providing a pivotal engagement between the links and panel.
5. In a drop end gondola car, the combination with the corner posts and end sill of the car, the latter extending outwardly beyond the corner posts, of an end panel, the lower edge of which is formed with slots, hinge forming links pivoted to the end sill at points outside of said end panel, and slotted keeper plates on the inner lower margin of the panel through the slots of which the links project, said links being formed with cross-pieces which lie between the panel and said keeper plates. 70
10. In a drop end gondola car, in combination, the corner posts of the car, an end sill on the outside of the corner posts having an upwardly extending flange which lies against said corner posts, an end panel, keeper plates on the inner lower margin of the end panel, said panel, flange and keeper plates being formed with alining slots, and links pivoted to the end sill, extending through said slots, and furnished with means providing a pivotal connection between said links and the panel. 75
15. In a drop end gondola car, in combination, the corner posts of the car, an end sill on the outside of the corner posts having an upwardly extending flange which lies against said corner posts, an end panel, keeper plates on the inner lower margin of the end panel, said panel, flange and keeper plates being formed with alining slots, and links pivoted to the end sill, extending through said slots, and provided with cross-pieces which lie in the spaces between said keeper plates and panel. 80
20. In a drop end gondola car, in combination, the corner posts of the car, an end sill on the outside of the corner posts having an upwardly extending flange which lies against said corner posts, an end panel, keeper plates on the inner lower margin of the end panel, said panel, flange and keeper plates being formed with alining slots, and links pivoted to the end sill, extending through said slots, and furnished with means providing a pivotal connection between said links and the panel. 85
25. In a drop end gondola car, in combination, the corner posts of the car, an end sill on the outside of the corner posts having an upwardly extending flange which lies against said corner posts, an end panel, keeper plates on the inner lower margin of the end panel, said panel, flange and keeper plates being formed with alining slots, and links pivoted to the end sill, extending through said slots, and provided with cross-pieces which lie in the spaces between said keeper plates and panel. 90
30. In a drop end gondola car, in combination, the corner posts of the car, an end sill on the outside of the corner posts having an upwardly extending flange which lies against said corner posts, an end panel, keeper plates on the inner lower margin of the end panel, said panel, flange and keeper plates being formed with alining slots, and links pivoted to the end sill, extending through said slots, and furnished with means providing a pivotal connection between said links and the panel. 95
35. In a drop end gondola car, in combination, the corner posts of the car, an end sill on the outside of the corner posts having an upwardly extending flange which lies against said corner posts, an end panel, keeper plates on the inner lower margin of the end panel, said panel, flange and keeper plates being formed with alining slots, and links pivoted to the end sill, extending through said slots, and provided with cross-pieces which lie in the spaces between said keeper plates and panel. 100
40. In a drop end gondola car, in combination, the corner posts of a car, an end sill outside said corner posts having an upstanding flange lying against the outside of the posts, an end panel, said panel and flange being formed with alining slots, keeper plates on the inner lower margin of the panel, and links pivoted to the sill, extending through said slots and provided with cross-pieces which lie between said keeper plates and the end panel. 105
45. In a drop end gondola car, in combination, the corner posts of the car, an end sill on the outside of said corner posts having an upstanding flange bearing against the outside of the corner posts, keeper plates on the inner lower margin of the panel, said keeper plates, panel and flange being formed with alining slots, links extending through said slots and provided with cross-pieces lying between the keeper plates and panel, and angular supports secured to the end sill against said upstanding flange to which the outer ends of said links are pivoted. 110
50. In a drop end gondola car, in combination, the corner posts of the car, an end sill on the outside of said corner posts having an upstanding flange bearing against the outside of the corner posts, keeper plates on the inner lower margin of the panel, said keeper plates, panel and flange being formed with alining slots, links extending through said slots and provided with cross-pieces lying between the keeper plates and panel, and angular supports secured to the end sill against said upstanding flange to which the outer ends of said links are pivoted. 115
55. In a drop end gondola car, in combination, the corner posts of the car, an end sill on the outside of said corner posts having an upstanding flange bearing against the outside of the corner posts, keeper plates on the inner lower margin of the panel, said keeper plates, panel and flange being formed with alining slots, links extending through said slots and provided with cross-pieces lying between the keeper plates and panel, and angular supports secured to the end sill against said upstanding flange to which the outer ends of said links are pivoted. 120
60. In a drop end gondola car, in combination, the corner posts of the car, an end sill on the outside of said corner posts having an upstanding flange bearing against the outside of the corner posts, keeper plates on the inner lower margin of the panel, said keeper plates, panel and flange being formed with alining slots, links extending through said slots and provided with cross-pieces lying between the keeper plates and panel, and angular supports secured to the end sill against said upstanding flange to which the outer ends of said links are pivoted. 125
65. In a drop end gondola car, the combination with the under frame of the car, of an end panel slotted at its lower edge comprising a horizontally corrugated metal sheet, links pivoted to the under frame of the car outside of the end panel, extending through said slots, and formed with cross-pieces at their inner ends, and U-shaped keeper plates, the edges of which are secured to the lower edge of the panel and the lowermost corrugation thereof respectively. 70
70. The combination with the under frame and flooring of a drop end gondola car, of an end panel formed with slots in its lower edge comprising a horizontally corrugated metal sheet, links pivoted to the under frame of the car outside of said end panel, extending through said slots, and formed on their inner ends with cross-pieces, and U-shaped keeper plates, the edges of which are secured to the lower edge of the panel and the lowermost corrugation thereof respectively, the rounded portions of the keeper plates resting on the flooring of the car when said panel is in upright position. 75
75. The combination with the under frame and flooring of a drop end gondola car, of an end panel comprising a horizontally corrugated sheet, U-shaped keeper plates having legs of unequal length, the short length being connected with the edge of the panel and the longer leg to the lowermost corrugation thereof, the intervening curved portion of the keeper plates providing a rocking bearing supporting the panel on the flooring of the car, and hinge forming elements pivoted to the under frame of the car outside of said end panel, the inner ends of which are provided with cross-pieces lying between the keeper plates and panel. 80
80. The combination with the under frame and flooring of a drop end gondola car, of an end panel, hinge forming links pivoted to the under frame of the car outside of said panel, and keeper plates providing a hinged engagement between the inner ends of the links and the lower edge of the panel, said keeper plates having rounded portions forming rocking bearings for the panel for supporting the panel on the floor. 85
85. The combination with the under frame and corner posts of a drop end gondola car, of an end panel comprising a corrugated metal sheet, a flat sheet riveted at intervals to said corrugated sheet, and means providing marginal flanges on the side and upper edges of the panel; and means for hinging the lower edge of the panel to the under frame of the car. 90
90. The combination with the under frame and corner posts of a drop end gondola car, of an end panel comprising a corrugated metal sheet, a flat sheet riveted at intervals to said corrugated sheet, and means providing marginal flanges on the side and upper edges of the panel; and means for hinging the lower edge of the panel to the under frame of the car. 95
95. The combination with the under frame and corner posts of a drop end gondola car, of an end panel comprising a corrugated metal sheet, a flat sheet riveted at intervals to said corrugated sheet, and means providing marginal flanges on the side and upper edges of the panel; and means for hinging the lower edge of the panel to the under frame of the car. 100
100. The combination with the under frame and corner posts of a drop end gondola car, of an end panel comprising a corrugated metal sheet, a flat sheet riveted at intervals to said corrugated sheet, and means providing marginal flanges on the side and upper edges of the panel; and means for hinging the lower edge of the panel to the under frame of the car. 105
105. The combination with the under frame and corner posts of a drop end gondola car, of an end panel comprising a corrugated metal sheet, a flat sheet riveted at intervals to said corrugated sheet, and means providing marginal flanges on the side and upper edges of the panel; and means for hinging the lower edge of the panel to the under frame of the car. 110
110. The combination with the under frame and corner posts of a drop end gondola car, of an end panel comprising a corrugated metal sheet, a flat sheet riveted at intervals to said corrugated sheet, and means providing marginal flanges on the side and upper edges of the panel; and means for hinging the lower edge of the panel to the under frame of the car. 115
115. The combination with the under frame and corner posts of a drop end gondola car, of an end panel comprising a corrugated metal sheet, a flat sheet riveted at intervals to said corrugated sheet, and means providing marginal flanges on the side and upper edges of the panel; and means for hinging the lower edge of the panel to the under frame of the car. 120
120. The combination with the under frame and corner posts of a drop end gondola car, of an end panel comprising a corrugated metal sheet, a flat sheet riveted at intervals to said corrugated sheet, and means providing marginal flanges on the side and upper edges of the panel; and means for hinging the lower edge of the panel to the under frame of the car. 125
125. The combination with the under frame and corner posts of a drop end gondola car, of an end panel comprising a corrugated metal sheet, a flat sheet riveted at intervals to said corrugated sheet, and means providing marginal flanges on the side and upper edges of the panel; and means for hinging the lower edge of the panel to the under frame of the car. 130

4

16. In a drop end gondola car, the combination of a folding end panel and a hinge for the same comprising a T-shaped link, a keeper plate on the panel providing a 5 pivotal connection between the head of the link and the panel, and means for pivotally mounting the other end of the link on the car.

17. In a drop end gondola car, the combination of a folding end panel and a hinge for the same comprising a T-shaped link, means providing a pivotal connection between the head of the link and the panel, and spaced supporting brackets on the car 15 for pivotally attaching thereto the other end of the link.

18. In a drop end gondola car, the combination of a folding end panel and a hinge for the same comprising a T-shaped link, 20 keeper plates on the panel providing a pivotal connection between the head of the link and the panel, and spaced supporting brackets for pivotally mounting the other end of the link on the car.

25 19. The combination with the end sill and folding end panel of a drop end gondola car, of a hinge for the panel comprising a

T-shaped link, means providing a pivotal connection between the head of the link and the panel, and means for pivotally mounting 30 the other end of the link on said end sill.

20. The combination with the end sill and folding end panel of a drop end gondola car, of a hinge for the panel comprising a T-shaped link, a keeper plate on the panel providing a pivotal connection between the head of the link and said panel, and spaced supporting brackets on the end sill providing 35 a pivotal connection for the other end of the link.

21. The combination with the end sill and folding end panel of a drop end gondola car, said panel being formed on its lower edge with a pair of slots, of hinges for said panel comprising, in each case, a T-shaped 40 link adapted to extend through one of said slots, keeper plates on the inside of the panel for providing a pivotal connection between the head of the link and the panel, and means on the end sill providing a pivotal 45 connection between the other end of the link and the sill.
